UNITED STATES PATENT OFFICE.

ANTON WARDZINSKI, OF BROMBERG, GERMANY.

FURNACE.

No. 909,488.

Specification of Letters Patent.

Patented Jan. 12, 1909.

Application filed August 27, 1907. Serial No. 390,286.

To all whom it may concern:

Be it known that I, ANTON WARDZINSKI, a subject of the German Emperor, and a resident of Bromberg, in the German Empire, 5 have invented new and useful Improvements in Furnaces, of which the following is a specification.

This invention relates to improvements in a smoke consuming furnace for boilers and 10 the like of that type in which heated or heat storing bodies are arranged and disposed behind the firebridge so as to be heated by the products of combustion. With such devices when the furnace door is opened for the introduction of a fresh charge of fuel the cold 15 air which enters the furnace and the fire gases which are cooled by such air are heated by the heat storing body with the result that the formation of soot is prevented and complete 20 combustion takes place.

According to my present invention the heat storing body which is placed just behind the firebridge is in the form of a truncated cone of refractory material axially perforated 25 with a central passage and pointing in the direction of travel of the fire gases. The central passage is in a horizontal plane and the cone is so placed relatively to the firebridge that the lower edge of the central passage is 30 about level with the upper edge of the firebridge. In line with the cone indicated is a second cone placed further along the flue and also pointing in the direction of travel of the fire gases.

35 In the firebridge is an air passage for heated air from the ashpit to enter the flue, and this air passage may be controlled from the furnace door.

In the accompanying drawings Figure 1 40 illustrates in vertical longitudinal section a boiler furnace and part of a flue. Fig. 2 is a view in elevation of the base of the refractory cone which is placed next to the firebridge.

45 Referring to the drawings, *a* indicates the firebars of the furnace and *b* the firebridge. Placed in the flue behind the firebridge is a cone *c* of refractory material disposed horizontally and having its base presented to the 50 firebridge. This cone is centrally axially perforated as at *d* and its base is formed or provided with ribs *e*, which may be disposed tangentially to the central perforation or in any other way which will have the effect of 55 securing a thorough admixture of the fire

gases impinging on the base with hot air which also impinges on the base and is admitted from the ashpit through the opening in the firebridge which is controlled by the damper *i*. 60

As will be seen the cone *c* is so placed in its support *g* that the lower edge of its central perforation is about level with the upper edge of the firebridge.

The door or damper *i* may be manipulated 65 by hand to admit air when desired, but it is preferred to connect it to the furnace door *m* by means of a rod *k* in such a manner that when the door is opened (as for the addition of a fresh charge of fuel) the damper is also 70 opened and heated air passes through the firebridge. Connected to the rods levers or the like by means of which the motion of the door *m* is communicated to the damper *i*, may be an oil pump, dash pot, clock or other 75 well known device commonly used for such a purpose, to check or control the period at which the damper closes after the furnace door is closed.

With the damper *i* opened as indicated at 80 the time when fresh fuel is being added, heated air is admitted and mixed with the large and comparatively cool quantities of gases then generated and arriving from the fire. This mixture is heated by contact with 85 the heated cone *c* and complete combustion finally takes place.

Behind the first perforated cone as already 90 described there is, as illustrated in the drawings, a second solid cone *f* arranged in such a manner that its base receives the gases which pass through the central perforation in the first cone.

Air is fed in through the channel *h* of the fire-bridge. One part of the air streams 95 through the hole *d* of the cone *c* and another part passes the spaces existing around the first cone. Both parts of air impinge against the second cone. It is clear that the highest efficacy of the second cone depends upon the 100 condition that the two cones be spaced from each other so that the second cone may be of use in heating the air that does not pass through the perforation.

More than two cones may be used, the 105 third being disposed in relation to the second as the second is to the first and so on through the series.

When more than two cones are used, the second or other cone may also be perforated. 110

I claim:—

1. The combination in a furnace of a firebridge having an opening communicating with the ashpit, a perforated cone of refractory material placed behind the bridge and with its base presented thereto, and a second cone placed in extension of the first and with its base presented thereto, substantially as herein described.
- 10 2. The combination in a furnace of a firebridge formed with an opening communicating with the ashpit, a damper for such opening, means by which the movement of the damper is controlled from the furnace door, a perforated cone of refractory material placed behind the bridge and with its base presented thereto, and a second cone placed in extension of the first and with its base pre-

sented thereto, substantially as herein described.

- 20 3. The coöperative combination in a furnace, of a firebridge having an air opening therethrough leading from the ashpit and a perforated cone of refractory material placed behind such firebridge and having a base provided with mixing ribs presented to such firebridge, substantially as hereinbefore described.

25 In witness whereof I have hereunto set my hand in the presence of two subscribing witnesses.

30 ANTON WARDZINSKI.
